UNITED STATES PATENT OFFICE.

RUFUS C. BREWSTER, OF LEWISBURG, WEST VIRGINIA.

FLY CHASER AND CATCHER.

Application filed July 20, 1923. Serial No. 652,787.

To all whom it may concern:

Be it known that I, RUFUS C. BREWSTER, a citizen of the United States, residing at Lewisburg, in the county of Greenbrier and State of West Virginia, have invented a new and useful Fly Chaser and Catcher, of which the following is a specification.

This invention aims to provide a simple and inexpensive means whereby flies may be driven off cattle and other animals, the flies being collected, within the casing portion of the structure, and the casing portion of the structure being so constructed that it can be washed, or be folded up into small compass and dipped into water or any other liquid to kill the flies, the casing being so made and supported that it can be adjusted vertically to accommodate animals of different heights.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in longitudinal section, a device constructed in accordance with the invention, parts being in elevation; Figure 2 is a cross section; and Figure 3 is a fragmental perspective.

In carrying out the invention, there is provided a flexible textile casing 1, made of cheese cloth or any other suitable material, the casing comprising a top 2, sides 3 and an end wall 4 extended between the sides 3 and downwardly from the top 2. Throughout its entire cross section, the casing 1 is open at one end, as shown at 5. A partition 6 extends between the sides 3 and inwardly from the lower edge of the end wall 4, the partition being connected to the sides and to the end wall, and forming a pocket 7 in the top of the casing, at one end thereof, the casing being open at said end, as at 8, below the partition 6.

Any suitable means may be provided for mounting the casing 1 for vertical adjustment, so that the partition 6 will be so located that the cattle may pass therebeneath. If preferred, an outer frame includ-

ing corner posts 9 may be supplied, the upper corners of the casing 1 carrying flexible elements 10, such as ropes, adapted to be tied about the posts 9. An inner frame is provided, the same including vertical posts 11 located close to the sides 3 of the casing 1. A cross piece 12 is supplied and supports the inner end of the partition 6, the posts 11 having vertically spaced openings 14 adapted to receive securing elements 15, such as bolts, mounted in the ends of the cross piece 12. The upper ends of downwardly diverging braces 16 are connected to the cross piece 12, the lower ends of the braces being connected to the posts 11 by securing elements 17, adapted to be mounted in any of the openings 14 of the posts 11.

Within the casing 1 and to the rear of the posts 11 are located fixed fly wipers 18 which, as shown at 19, converge inwardly toward the vertical median plane of the casing 1. As shown at 20, the wipers 18 slant upwardly and forwardly, the wipers being of approximately conical form, as indicated at 21, the upper ends of the wipers being located closely adjacent to the cross piece 12 and the rear end of the partition 6. The wipers 18 preferably are pieces of cedar brush, this material being used because the fronds of cedar brush are flexible and present a large wiping surface, without being unduly stiff. Further, cedar brush grows naturally in a conical form. It is advisable to use brush in the making of the wipers 18 because cattle will pass through brush readily, without suspicion, it being unnecessary to goad or drive the animals through the casing 1, when brush is used.

In practical operation, the cattle are driven through the casing 1, entering at the end 5 and leaving at the end 8. The brush wipers 18 sweep the flies off the bodies of the animals, from the hoofs up, the flies being directed forwardly and upwardly by the wipers and being caused to collect in the pocket 7 above the partition 8. The cattle, passing between the braces or guides 16, move beneath the partition 6, and out of the open end 8 of the casing, as aforesaid.

The flexible elements 10 may be shifted vertically on the posts 9, thereby raising and lowering the partition 6 and adapting the device to cattle of different heights, the cross piece 12 being shifted vertically on the posts 11, along with the braces 16, so as to

support the rear edge of the partition 6 when the same is raised or lowered with the sides 3 and the end wall 4 of the casing 1.

The casing 1 may be detached readily from the posts 9 and be washed, because it is made of some light textile material, such as cheese cloth, the casing, although of large size when set up, occupying but little space when folded. The casing 1 may be folded up in such a way as to trap the flies in the pocket 7, and by dipping the casing into liquid, the flies may be killed.

I claim:

In a device of the class described, a casing comprising a top, sides, an end wall, a partition extended inwardly from the end wall and between the sides, to form a fly

pocket and a run way therebeneath, an outer frame, means for securing the casing to the outer frame for adjustment to vary the position of the partition and the height of the run way, and an inner frame in the casing, the inner frame comprising vertically adjustable parts supporting the partition, and means for holding said parts of the inner frame in vertically adjusted positions.

In testimony that I claim the foregoing as my own, I have hereto affixed my mark in the presence of two witnesses.

RUFUS C. BREWSTER.
